UNITED STATES PATENT OFFICE.

FRANK M. JEFFERY, OF JERSEY CITY, NEW JERSEY.

BUSTLE.

SPECIFICATION forming part of Letters Patent No. 378,964, dated March 6, 1888.

Application filed October 27, 1887. Serial No. 253,528. (No model.)

To all whom it may concern:

Be it known that I, FRANK M. JEFFERY, a citizen of the United States, and a resident of Jersey City, Hudson county, New Jersey, have 5 invented certain new and useful Improvements in Bustles and in Springs Adapted for Distending Same, of which the following is a specification.

My invention relates to that class of bustles 10 wherein torsion-springs are employed for distending the bustle; and the distinguishing characteristic of my invention lies in the peculiar construction and arrangement of the torsion-springs employed.

15 My invention will be fully described hereinafter, and its novel features carefully defined in the claims.

In the drawings, which serve to illustrate my invention, I have shown it embodied in several forms of bustles.

Figures 1, 2, 2^a, and 2^b illustrate the application of my invention to a bustle wherein the bows are all hinged on a common hinge-axis, Fig. 1 being a plan of the bustle, Fig. 2 a section of same on line 2 2 in Fig. 1, and Fig. 2^a 25 a perspective view of the torsion-spring detached. Fig. 2^b illustrates another mode of arranging the spring. Figs. 3 and 3^a illustrate another form of the bustle, wherein plain wire 30 is employed for the bows, Fig. 3 being a perspective view of the bustle, and Fig. 3^a a view of the torsion-spring detached. Figs. 4 and 4^a 35 illustrate a bustle of another form embodying my invention, Fig. 4 being a sectional elevation similar to Fig. 2, and Fig. 4^a illustrating a modification of the construction shown in Fig. 4. This figure (4) shows a long or deep bustle provided with my spring. This spring 40 is precisely like that illustrated in Fig. 1 and extends across the bustle from side to side. Fig. 4^b is a fragmentary detail view.

I will first describe the construction illustrated in Figs. 1, 2, and 2^a. These views represent a bustle having bows A A made from 45 what is known as "twin-wire" fabric, hinged on common hinge-axes a a in a well-known manner, strained by a strip of webbing, b, provided with a buckle and connected by a flexible strip, c.

50 B represents the usual belt for attaching the bustle to the waist of the wearer.

So far as described, the bustle presents no especially novel features. It may be collapsed by upward pressure on the lower bow, the bows closing together and up to the upright 55 bow.

To keep the bows distended normally and elastically, I employ a peculiarly-constructed compound torsion-spring, C. (Shown detached in Fig. 2^a.) This spring comprises two like 60 torsion-springs of wire, arranged side by side, but in relatively-reversed positions. For convenience of description I have lettered one of these springs d and the other d^x in Fig. 2^a, and have distinguished the corresponding parts of 65 each by adding the character x to those of spring d^x. Spring d has two arms, bent in opposite or different directions, on its ends, and spring d^x has two arms, e e^x, bent in opposite or different directions on its ends. In 70 fact the two springs are alike in form, and they are tied together or connected loosely together by a tube, f, slipped over them before the arms e e^x are bent thereon. This tube is only designed to keep the springs in place, 75 and it does not bind them tightly. In Fig. 2^a said tube is shown partly broken away to expose the inclosed springs. On the ends of the arms e e^x are formed loops or eyes g g, and these eyes engage and turn on studs or rivets 80 h h (see Fig. 2) in the terminal or outer bows of the bustle and keep the latter distended.

By inspection of Fig. 2^a it will be seen that the arms e e^x of the spring C stand normally, when not under tension, nearly opposite to 85 each other, or, substantially, one hundred and eighty degrees apart; but when under normal tension in the bustle, as seen in Fig. 2, they stand less than ninety degrees apart, under which condition they exert a very considerable distending strain on the bows of the bustle. In bending the arms on the ends of the springs they may, if desired, be bent oppositely to each other, or at any angle that will put them under proper tension when in place. The 95 body parts of the spring-wires d d^x, in which the torsion is produced, extend across the bustle, (see Fig. 1,) and the spring C is connected with the bustle at both sides of the latter.

100 In Fig. 2^b, which is a perspective view of a bustle with the bows partly broken away, A

A represent the bows or the hinging ends thereof, and C the torsion-spring. In this construction the springs $d d^x$ pass through eyelets or holes in the bows at the hinging points $a a$ and form the hinging pivots. The arms $e e^x$ extend up along the terminal bows and are secured thereto at their ends in some suitable manner, as by means of spangles $k k$. To keep the springs $d d^x$ together, and to add strength, also, to the spring, I employ a third spring or wire, d' , which lies alongside of the other two, is coiled snugly around them at f' , just inside the bows, and has its oppositely-bent arms e' attached one to the upright terminal bow at one side and the other to the horizontal terminal bow on the other side. In the figure some of the spring-arms are indicated by dotted lines only.

I will now describe the form of bustle illustrated in Figs. 3 and 3^a. This bustle is made from plain wire, and the upright bow A^x has its lower ends bent back and forth, so as to form parallel hinge-bearings a^x , to receive hinging-coils a' on the ends of the several bows A. These coils a' are not springs, but simply elongated hinge-eyes, which loosely embrace their bearings a^x . The bows are connected by a strip or strips, e, usually of tape or webbing. Fig. 3^a shows the torsion-spring C, for distending the bustle. This spring is substantially the same as that shown in Fig. 2^a, except in these respects: Instead of eyes formed on the ends of arms $e e^x$, these latter are made to couple below to the lower bow A at the points h^x , and above to one of the hinge-bearings a^x , as seen in Fig. 3; also, in lieu of a tube for connecting the springs $d d^x$, as shown in Fig. 2^a, I employ two short sleeves or coils of wire, as f^x , formed separately from the springs. Any simple connecting device may be employed for this purpose. I have shown three such devices in Figs. 2^a, 2^b, and 3^a.

b is a lacing-cord for straining the bustle. This cord is passed through the bights formed in the bends at the lower part of bow A^x.

I will now describe the form of bustle illustrated in Figs. 4 and 4^a. These views show the application of my torsion-distending-spring C to a long or deep bustle.

E represents one of two upright strips of broad stout webbing, one arranged at each side of the bustle to form a support for the ends of the bows.

A A are the horizontal projecting bows made from twin-wire fabric and secured at their opposite ends to the broad side strips, E, each by two rivets, eyelets, or other suitable fastening devices.

A^x is the upright bow of the bustle, secured at its ends to the upper ends of the strips E and to the uppermost bow A.

A' A' are intermediate bows hinged to the upper bow A. All the bows are connected by a flexible strip, c.

65 The flexibility of the side strips, E, allows the bows to collapse upward, either by direct upward pressure, the bows A remaining sub-

stantially horizontal, or by a swinging movement of the bows on their points of attachment.

70 C C are two torsion-springs, like that before described—that is to say, the bodies of the springs extend across the bustle from side to side, as in Fig. 1. Fig. 4 shows clearly how they are mounted in the bustle, their arms being connected to the bows at i i between the two attaching-rivets of the bow.

75 It may sometimes be desirable to add an auxiliary bow to the bottom of the bustle, as that lettered A² in Fig. 4, in which case I employ a small coil spring, C^x, one at each side of the bustle, to properly distend it below the springs C. This spring is a simple coil with its ends or branches attached in the same manner as are those of springs C.

80 In Fig. 4^a, which is a fragmentary elevation, I have shown crossed chains E^x in lieu of the flexible side strips, E. Any suitable flexible material providing two attaching points for the bow may be employed for this purpose.

85 By attaching the ends of the spring-arms to the bows between the rivets or clips by which the bows are attached, the spring serves to hold the strips E rigidly distended and the bows A A projecting out therefrom, as will be 90 understood.

95 In Fig. 4, b^x represents one of the lacing-flies of the bustle, such as are usually employed. The flies are attached to the side strips, E, by means of stiff metallic angle-clips j j. In Fig. 100 4^a, which is an enlarged sectional detail view designed to illustrate the manner of employing this clip j, E is the side strip, (seen in cross-section,) A is one of the bows of the bustle, b^x is the lacing-fly, and j is one of the clips 105 for securing the fly to the side strip and bow. The clip is cut or stamped from sheet metal and provided with a hole at each end to receive the attaching rivets or eyelets, and then 110 bent to the angular form shown. In Fig. 4 I have shown one of these clips at the end of each bow A, and secured by one of the rivets or eyelets that secure the bow to the side strip, E. The clip is interposed between the end of the bow and the person of the wearer, and the 115 fly extends or may extend laterally beyond the side of the bustle, so as to be interposed between the clip and the person of the wearer. This clip forms an economical and convenient means of connecting the fly b^x to the bustle, 120 and it may be used on any bustle having an upright side frame to which the fly is secured.

125 Of course the torsion-spring C may be made of more than two wires where a stiffer spring is required; but I find that two or three steel wires will suffice for an ordinary bustle.

When the spring is applied to a bustle, it is not material whether the arms project outward, as in Fig. 2^b, or inward, as in Figs. 1 and 2, and the wire of the spring may have 130 any form of cross-section—round, square, &c. Thin flat steel may be used for the bows in lieu of plain or twin wire. Any ordinary material may be used.

I do not desire to be understood as broadly claiming a torsional spring of wire with an arm bent on its end. Such springs have been heretofore employed, though not, so far as I 5 am aware, for distending a bustle. My spring has these characteristics, namely: It has a body composed of two or more connected wires, and each wire has two arms—one on each end—bent in opposite directions. These arms are 10 attached at their free ends to the bows or frames of the bustle in such a manner as to distend the bustle.

Having thus described my invention, I claim—

- 15 1. In a bustle, the combination, with the bows and with a connector that limits their distention, of a torsional distending-spring consisting of two or more springs which have main or body portions loosely connected and 20 extending across the bustle, and at the opposite ends of these main portions acting-arms, the arms of each spring being bent in different directions and attached at their free ends to the bows of the bustle, whereby the lateral 25 expansibility of the series of bows is limited by the length of the said torsional spring, substantially as set forth.
2. In a bustle, the combination, with the bows and a flexible connector that limits their 30 distention, of a torsional distending-spring consisting of two or more springs which have main or body portions loosely connected and extending across the bustle, and at the oppo-

site ends of these main portions acting-arms, the arms of each spring being bent in different directions and attached at their free ends to the bows of the bustle, said springs being arranged within the hollow of the bustle with their several arms directed forward, substantially as set forth. 35

3. In a bustle, the combination, with the flexible side strips, as E, of the projecting bows, as A, each end of which is attached to said strips at two points, as described, the torsional distending-spring C, arranged in the 40 hollow of the bustle and having the free ends of its arms attached to the respective bows A between the points of attachment of the bows to the side strips, and means for attaching the bustle to the person of the wearer, substantially 45 as set forth.

4. The combination, with the flexible side strips, as E, of a bustle, the projecting bows, as A A, attached at their ends to said strips, the torsional distending-springs, as C, arranged 50 as described, and means for attaching the bustle to the person of the wearer, of the lower bow, as A², and the coiled distending-springs C^x, substantially as set forth. 55

In witness whereof I have hereunto signed my name in the presence of two subscribing witnesses.

FRANK M. JEFFERY.
